CLAIM

I claim the ornamental design for an adapter plate for use with mounting systems for audio/visual devices or the like, as shown and described.

DESCRIPTION

FIG. 1 is an isometric view of the claimed design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The ornamental design which is claimed is shown in solid lines in the drawings. The broken lines in the drawings form no part of the claimed design.

1 Claim, 5 Drawing Sheets(56)
